DENTAL MIRROR OR SIMILAR ARTICLE

Jacob C. Butler, Flossmoor, Ill., assignor to The William Getz Corporation, Chicago, Ill., a corporation of Illinois

Filed Mar. 2, 1961, Ser. No. 64,118

Term of patent 14 years

(Cl. D24—1)

FIG. 1 is a perspective view taken from one side of a dental mirror or similar article showing my new design;
FIG. 2 is an elevational view of the opposite side thereof;

FIG. 3 is a fragmentary elevational view thereof taken on line 3—3 of FIG. 2;

FIG. 4 is a vertical sectional view thereof taken on line 4—4 of FIG. 2;

FIG. 5 is a vertical sectional view thereof taken on line 5—5 of FIG. 2; and

FIG. 6 is a fragmentary elevational view thereof taken on line 6—6 of FIG. 2.

The characteristic features of my design for the dental mirror disclosed reside in the configuration of the mirror head.

I claim:

The ornamental design for a dental mirror or similar article, as shown and described.
